DISPLAY DEVICE.

1,075,006.

Specification of Letters Patent. Patented Oct. 7, 1913.

Application filed April 5, 1912. Serial No. 686,639.

To all whom it may concern:

Be it known that we, ALFRED F. BIPPUS, HERBERT KEMPTHORN, and GEORGE J. PASCOE, citizens of the United States, residing at Toledo, Lucas county, Ohio, have invented a new and useful Display Device, of which the following is a specification.

This invention relates to display devices.

This invention has utility when embodied in card displays incorporating special features of attraction therein.

Referring to the drawings: Figure 1 is a transverse vertical section with intermediate portion broken away of an embodiment of the invention in a card display; Fig. 2 is a fragmentary front view thereof; Fig. 3 is an enlarged detail of a catch feature for the carriers of the cards; Fig. 4 is an enlarged detail of the trip off feature of the catch of Fig. 3; Fig. 5 is a fragmentary detail of another catch device; Fig. 6 is a detail in side elevation of said catch of Fig. 5; and Fig. 7 is a transverse section of a portion of the carrier showing the card mounting lock.

The housing 1 has in the lower portion thereof the prime mover or motor 2 driving worm 3 coacting with the worm wheel 4 on the shaft 5 for speed reduction driving through the belt 6 on the shaft 7 carrying sprocket wheels 8 for the endless belt or carrier chains 9 which pass over sprocket wheels 10 similar to sprocket wheels 8. The sprocket wheels 10 are mounted on the shaft 11 in the frame 1, parallel to the shaft 7 in said frame. The front portion of the frame 1 adjacent the sprocket wheels 10 is closed by the panel 12, while the lower portion of the frame is closed by panel 13. Between these panels 12 and 13 the frame or housing 1 is closed by the panel 14 having sight or glass section through which the display of cards may be seen. At spaced intervals along the chains 9, these chains 9 are connected by rods 15 passing through slots 16. The ends of the slot 16 have rubber buffers 17. These buffers 17 and slot 16 are features of the end channels 18 of the carrier, which end channels 18 are connected by transverse channels 19 for card display housings or carriers. In these channels 19 are bolts 20 engaging the wedge channel sections 21 to force the cards 22 into locking relation to the channel 19 as the bolt 20 is rotated relatively to its nut 23 in drawing the wedge 21 into the channel 19. This serves as an efficient and most positive lock

for holding the cards in fixed position in the card carriers. The cards in the carrier are disposed so that when one card is right side up, the opposite card is wrong side up so that as the cards travel with the right side card 22 for exposure, in passing downward past the view panel 14, it travels about the lower sprocket wheel 8, thence up about the upper sprocket wheel 10, and in passing thereover, the lower portion contacts the shaft 11 so that as the travel of the belt 9 continues the carrier at what was the upper portion in the circuit of travel just described is brought into a lower position and rides into contact with the catch 24, which is brought into horizontal position by the spring 25 and so held by the dog 26 thrown into locking relation therewith by the spring 27. This stop 24 and dog 26 are mounted on the link 28, the upper portion of which is carried by link 29 pivoted to the housing and normally urged to upward or horizontal position by the spring 30, the tension of which may be adjusted by the nut 31. To cause the link 28 to always be disposed in a vertical position, there is connected thereto the L-link 32 similar to the link 29, which link 32, beyond its pivot to the frame 1 has the counterweight 33. The spring 30 and the counterweight 33 are counterpoised for normally holding the links 29, 32, in such position that the catch 24 may be in the path of the card carrier as it goes over the wheel 10 and catch said card carrier from dropping and allow the chain 9, in its carrying of the rod 15, to move the card carrier to start the catch travel and with this impetus the counterpoising of spring 30 and counterweight 33 is overcome by the weight of the carrier and the carrier is allowed to move faster than the chain 9 as the carrier slides in its slot 16 along the bar 15. This movement of the catch 24 from its position as shown in Fig. 1 to its position as shown in Fig. 3 takes up the momentum of the card carrier to prevent any undesirable noise in the operation of the card display device and as the card carrier reaches its limit of movement the dog 26 strikes the stop 34 and is tripped to allow the card carrier to pass on in its circuit displaying the opposite side of the card to that displayed in its previous passage.

With the card carrier tripped off, the spring 30 and the counterpoise 33 bring the catch back into position for receiving the

next card carrier. This counterpoising may be by the spring 30 or by the counterweight 33 alone as may be found desirable. When in this recover position the catch stop 24 is 5 just clear in its horizontal position of the card carrier which has been released so that it will only engage the carrier which is slanted or not traveling truly vertical. In this sliding of the card along its rod, the rod 10 is at the opposite end to the position in the carrier which it had in the previous circuit as described. To insure this fall or slide of the card carrier, an incline or guide 35 is provided from the shaft 11 to the buffer 36 15 which is so disposed as to the carrier as to take up any lateral vibration and quiet as well as steady the carrier. Continuing from this buffer 36 is the guide 37 which is a guide not only for the card carrier but also 20 for the chain 9. Below this guide 37 there is the guide 38 for the chain 9 only, while there is the guide 39 for the card carriers some of which at this point may be reversed for change in the card display while in the 25 sight instead of being reversed only in the regular order of once in a circuit, as passing about the wheel 10. Opposed to this guide 39 there is mounted in the side of the housing 1 a pivot bracket 40 from which extends outwardly the arm 41 having the stop extension 42 so that the spring 42' on the pivot 41 normally urges this arm 42 against the front side of the housing which maintains the rigidly connected lower arm 43 in 30 normal vertical position to pass, without reversing, all card carriers not equipped with the guide 43'. When a card carrying the guide cam 43' comes along, the cam 43' engages the arm 41 and as the pivot point 40 35 is fixed, this rocks the arm 43 outwardly or toward the sight, so that as the carrier continues its travel with the sprocket chain, it has its lower portion come into engagement with the hook 44. Further traveling of the 40 chain 9 causes the bar 15 to slide toward the 45 bottom of the slot 16 and thus rock the top of the card inward along the guide 39 effecting a half rotation of the card carrier to display the opposite side of said card for the balance of the sight distance. This hook 44 which engages the lower portion of the 50 card carrier is mounted on the stem 45 rockably carried by the bracket 46 mounted on the side of the housing 1. Keyed to this 55 stem 45 is the counterweight 47 normally holding the hook in a slightly downward position for proper nesting of the card carrier as it comes to this point in its travel. As the card is thus slightly held against free 60 rocking in its half rotation, there is no permissible vibration for the hook swings upward, to release the card on its completed half turn. When the card has moved out of the hook, the hook is swung back by the 65 weight 47 and this backward swing is noise-

less for the weight 47 on its return to normal position hits the buffer 48 which buffer 48, besides having a padded face, may also yield as it has a spring back 49. The buffer 48 is mounted on the bracket 50 connected to 70 the frame 1. These shock absorbers or card quieting schemes in card carrier reversal comprising the hook 44 as well as the catch 24 keep the card carriers in the line of travel after they reverse with a maximum of quietness insuring noiseless operation of the mechanism as a whole and by these turning or reversal schemes a minimum of clearance 75 between the sight and the carrier is permissible, thus producing a housing of less 80 cumbersome proportion and a good view to be had in the sight.

Disposed at various points back of the frame for the sight 14 may be incandescent lamps 51 for illuminating the display of 85 the cards when run at night.

In the mechanism as disclosed, the parts 90 may be duplicated at each end of the housing 1 and in the device as shown the mechanisms are so used.

This structure requires but very little power in its operation and is most compact, permitting regular change of view once in each cycle so that double capacity may be had for each card carrier in that cards may 95 be displayed from each side thereof while the added feature of attractiveness, that of turning or reversing a card while in the sight, may be incorporated as to some of the card carriers and when this feature is in- 100 tervallent with the straight passage by the sight of other cards, there is enhanced utility in the device as a display structure. The catches are jacketed with rubber or other sound deadening material.

What is claimed and it is desired to secure by Letters Patent is:

1. A display device comprising an endless belt, a freely swingable suspended carrier 110 slidably pivoted thereon and catch means effecting the sliding of the carrier to reverse said carrier.

2. A display device comprising an endless belt, an invertible carrier loosely mounted thereon, carrier inversion means embodying 115 a catch mechanism including a yieldable carrier engaging seat effective to engage and retard the carrier during the inversion thereof.

3. A display device comprising an endless belt, a driving device for the belt, a wheel over which said belt passes, a suspended carrier, mounting means for suspending said carrier on said belt, said mounting means permitting movement of the carrier longitudinally of the belt, means to move the carrier longitudinally of the belt, and impact take-up means adjacent said wheel engaging the suspended carrier for retarding the carrier in its travel longitudinally of the belt.

4. A display device comprising a traveling carrier, a support slidably mounting said carrier, and carrier inversion means including a movable catch for engaging and retarding the carrier during said inversion. 40
5. A display device comprising a carrier, a driving device for the carrier, said carrier being capable of longitudinal movement relatively to the driving device, there being means to move the carrier longitudinally of the driving device, and catch mechanism including a movable seat, and means for resisting movement of said seat as the carrier in moving longitudinally of the driving device is received by said seat to effect quiet travel of the carrier in said movement. 45
6. A display device comprising a carrier, a driving device for the carrier, said carrier being capable of longitudinal movement relatively to the driving device, there being means to move the carrier longitudinally of the driving device, and catch mechanism including a pivoted seat and loading means for resisting movement of said seat as the carrier in moving longitudinally of the driving device is received by said seat to effect quiet travel of the carrier in said movement. 50
7. A display device comprising a carrier, a driving device for the carrier, said carrier being capable of longitudinal movement relatively to the driving device, there being means to move the carrier relatively to the driving device, and catch mechanism including a movable seat for receiving the carrier in its travel and guiding the carrier to move independently of the driving device, and a trip off for freeing the carrier from said seat. 55
8. A display device comprising a carrier, a continuously traveling mounting to which said carrier is slidably connected, catch mechanism for receiving the carrier to effect inversion of the carrier by sliding of the carrier relatively to its traveling mounting, and a guide for directing the carrier toward the catch. 60
9. A display device comprising an invertible carrier, a traveling support on which said carrier is slidably pivoted, there being means to cause the carrier to move independently of said traveling support, a driving device for the support, and a yieldable carrier engaging catch guiding the carrier to travel independently of its traveling support and limiting the carrier swing on carrier inversion. 65
10. A display device comprising an invertible carrier, an endless traveling support for the carrier upon which said carrier is pivoted, said carrier being capable of longitudinal movement relatively to the traveling support, there being means to cause the carrier to move relatively to said support, a driving device for the support, and a movable carrier engaging catch yieldable to the action of the carrier for guiding the carrier to travel independently of its traveling support and limiting the carrier swing on carrier inversion. 70
